STEEL WATER ARCH AND SIPHON.

Application filed October 9, 1925. Serial No. 61,527.

This invention relates to locomotives, and more particularly to what we term a steel water arch and siphon.

One of the main objects of the invention is to provide a fire arch for a locomotive boiler which may be constructed of suitable tempered sheet steel and which will utilize the heat generated in the fire box of the locomotive to the greatest possible advantage. A further object is to provide a water arch which will produce a siphoning effect when in use insuring thorough circulation of the water throughout the boiler so as to obtain uniform heating thereof thus eliminating severe stresses and strains due to different temperatures at different parts of the boiler. Another object is to provide an arch which will also act as a siphon in such manner as to cause water to flow continuously over the crown sheet of the fire box, the siphoning effect causing a continuous flow of water from the lower to the upper portion of the arch so as to bring the water to the source of heat and insure quick generation of a comparatively great quantity of steam for a given amount of fuel consumed. A further object is to provide an arch of this character which, when applied, will act to materially reinforce the fire box construction. Further objects will appear from the detailed description.

In the drawings:

Fig. 1 is a central vertical section taken through the arch as applied and associated parts of the locomotive boiler.

Fig. 2 is a section taken substantially on line 2—2 of Fig. 1.

Fig. 3 is a section taken substantially on line 3—3 of Fig. 1.

Fig. 4 is a fragmentary plan view looking down on the crown sheet taken substantially on line 4—4 of Fig. 1.

Fig. 5 is a perspective view of the arch and siphon.

The arch includes a body 1 formed of sheet metal of suitable gauge and temper from the lower forward end of which projects an extension 2. The body 1 is provided at the upper end of each side thereof with an extension forming a siphon element 3, and the end wall 4 of the body connecting these elements is curled downwardly and inwardly as shown. The structure thus produced is provided with a continuous peripheral flange 5 at each side by means of which

the structure is secured by welding to the side plates of fire box *b* of the locomotive boiler *B*. The sides of body 1 and extension 2, as well as the siphon elements 3, have direct communication with the water space *s* surrounding the fire box so that the water taken from this space can flow directly into the arch and siphon from both sides thereof. As more clearly illustrated in Figure 4, the siphon elements 3 extend inwardly and open through the crown sheet *c* of the fire box forming, in effect, tubular extensions of body 1 which are so disposed that water discharged through elements 3 will flow onto and over the crown sheet *c*. This feature of the construction is of importance as preventing injury to the crown sheet such as will occur if water were not continuously supplied thereto.

The products of combustion from the fire box *b* flow over and about the arch, a portion of these products flowing through the space *s* between the siphon elements 3 and into the combustion chamber *d*, the remaining portion of the products of combustion flowing over the entire face of body 1 and about extension 2 thereof, the products of combustion then flowing from combustion chamber or space *d* through flue tubes *e* which are secured through flue plate *f*. The water in the arch and siphon member is exposed directly to the intense heat of the fire box, where the greatest amount of heat is generated in a locomotive boiler, as is known, and is quickly heated to a very high temperature so as to produce steam in great quantities. The water which is thus heated rushes upwardly from extension 2 through body 1 and is caused to flow about the arched or curved top wall 4 in opposite directions into the siphon elements 3 from which the water is projected and is sprayed onto and over the crown sheet *c*. The water which flows upwardly through the body 1 is replaced by water which flows into extension 2 from the rearward lower portion of barrel *g* of the boiler. This causes a continuous circulation of water from the lower portion of the barrel of the boiler upwardly through the arch and siphon structure, the water from this structure flowing forwardly in the barrel of the boiler so that a continuous circulation is maintained throughout the whole length of the boiler structure. This insures uniform heating of the water within the

boiler and prevents severe stresses due to uneven heating of the water, that is, due to the water at the lower portion of the boiler being of a much lower temperature than the water at the upper portion thereof. In this connection it is to be noted that extension 2 communicates with the water space adjacent the lower portion of the barrel *g* of the boiler, this extension being positioned approximately at what is known as the "mud pot" portion of the boiler. This insures thorough and rapid circulation of the water and very even heating thereof, resulting in generation of a comparatively great quantity of steam for a given amount of fuel consumed. In this connection, it will be noted that the water flowing through the arch and siphon structure is forced to flow in a comparatively thin, flat sheet which is exposed at its upper and under sides, as well as its top and lower edges, to the direct action of the products of combustion from the fire box *b* so as to be quickly heated to a high temperature and converted into steam. This rapid heating and consequent rapid circulation of the water through the arch and siphon structure causes the water to be discharged through elements 3 at such velocity that the water will be sprayed around and will flow over the crown sheet *c* in the event that the level of the water in the boiler falls appreciably below the crown sheet, thus preventing serious injury to the crown sheet or possible serious accidents due to the water level in the boiler being below the normal safety level. As the water is distributed uniformly throughout the arch and siphon structure, all possibility of the formation of a dry spot, or of the forming of a steam pocket, with consequent injury to the arch or danger of exposure is eliminated.

As the combined arch and siphon is secured to the side portions of the fire box structure it serves to materially reinforce the fire box, particularly in view of the fact that this device is of hollow construction. To impart additional strength and rigidity to the arch and siphon structure, body 1 is arched slightly upwardly and inwardly, as illustrated in Figure 1, and this structure, as well as the fire box construction is provided with suitable spaced stay bolts secured thereon in a known manner.

As will be understood, and as above indicated, changes in the construction and ar-

angement of parts can be resorted to without departing from the field and scope of the same, and we intend to include all such variations as fall within the scope of the appended claims, in this application in which the preferred form only of our invention is disclosed.

What we claim is:

1. In combination with the fire box of a boiler, a combined arch and siphon structure including a comparatively thin hollow body extending across the fire box and secured to the side walls thereof, the body being inclined downwardly toward one end of the fire box and being provided at its lower end with an extension disposed approximately horizontally, the body being provided at its upper end with lateral extensions opening through the crown sheet of the fire box, the body and the extension thereof opening through the side walls of the fire box.

2. In combination with a boiler including a fire box, an arch and siphon structure including a comparatively thin hollow body inclined downwardly and forwardly of the fire box and provided at its lower end with an extension disposed substantially horizontally, the body being provided at its upper end with lateral extensions secured to and opening through the crown sheet of the fire box and with a downwardly curved top wall connecting said lateral extensions at the lower ends thereof, the body and the lower extension thereof being secured to and opening through the side walls of the fire box.

3. In combination with a boiler including a fire box, an arch and siphon structure including a comparatively thin hollow body inclined downwardly and forwardly of the fire box and provided at its lower end with an extension projecting forwardly in the fire box, said body being further provided at its upper end with lateral extensions secured to and opening through the crown sheet of the fire box and with an arcuate top wall connecting the lower ends of said extensions, the body and the extension at the lower end thereof being secured to and opening through the side walls of the fire box, said body being arched longitudinally.

In testimony whereof we affix our signatures.

GEORGE D. MCLEOD.
